UNITED STATES PATENT OFFICE.

JAMES A. REEDER, OF MEMPHIS, TENNESSEE.

FOLDING COOP.

1,136,269.

Specification of Letters Patent. Patented Apr. 20, 1915.

Application filed August 12, 1914. Serial No. 856,429.

To all whom it may concern:

Be it known that I, JAMES A. REEDER, a citizen of the United States, residing at Memphis, in the county of Shelby and State 5 of Tennessee, have invented a new and useful Folding Coop, of which the following is a specification.

The device forming the subject matter of this application is a collapsible coop and 10 the application discloses a structure which when not in use may be collapsed readily, to occupy small space, the construction being such that, at the will of an operator, the coop may be opened and set up, without 15 the use of tools.

The invention aims to improve the end walls of the coop and to provide end walls which, when folded beneath the bottom, co-operate in a novel manner with sundry other 20 elements of the structure.

It is within the scope of the invention to improve generally and to enhance the utility of devices of that type to which the present invention appertains.

25 With the above and other objects in view which will appear as the description proceeds the invention resides in the combination and arrangement of parts and in the details of construction hereinafter described 30 and claimed, it being understood that changes in the precise embodiment of the invention herein disclosed can be made within the scope of what is claimed without departing from the spirit of the invention.

35 In the accompanying drawings: Figure 1 shows in perspective, a collapsible or folding coop embodying the present invention; Fig. 2 is an end elevation of the coop; Fig. 3 is a fragmental side elevation showing one 40 of the end walls of the coop folded beneath the bottom of the coop; Fig. 4 is a bottom plan showing one of the end walls folded beneath and against the bottom of the coop, Fig. 4 being fragmentary in its disclosure;

45 Fig. 5 is a fragmental bottom plan of the coop showing one of the end walls in the position which the same is made to assume in Fig. 1; Fig. 6 is an end view of the coop, the structure being collapsed; Fig. 7 is a 50 perspective depicting one of the connecting bars which enter into the construction of the end walls of the coop.

The bottom of the coop comprises longitudinal bars 1 and bottom slats 2 disposed 55 transversely of the longitudinal bars and

secured thereto, the bottom slats being spaced from each other. Located between the longitudinal bars 1 and secured to the bottom slats 2 is a platform 3. The sides of the coop are made up of slats 4 disposed 60 in alternating relation to the bottom slats 2, the side slats 4 being spaced from each other. Pivot rods 5 extend through the ends of the bottom slats 2 and through the ends of the side slats 4. The top of the coop is 65 made up of slats 6 spaced apart and alternating with the side slats 4. Through the upper ends of the side slats 4 and through the extremities of the top slats 6 extend pivot rods 7. The bottom, the top and the 70 side walls of the coop, therefore, are connected in such a manner that the coop may be collapsed or flattened down as shown in Fig. 6. Secured to the upper face of the top slats 6 are longitudinal bars 8. Certain 75 of the top slats 6 terminate at the longitudinal bars 8 to define an opening in the top of the coop. The opening thus formed is closed by a lid comprising side bars 9 and slats 10 connecting the side bars. The side 80 bars 9 lie between the bars 8. A pivot rod 11 is terminally mounted in the bars 8 and passes through the side bars 9 of the lid to form a hinged mounting therefor. Mounted upon one of the top slats 6 is a latch 12 of 85 any desired construction, adapted to coact with the lid to hold the same closed.

The ends of the coop are composed of connecting bars 14 and slats 15 uniting the connecting bars. The connecting bars 14 lie 90 outside of the longitudinal bottom bars 1. Through the ends of the longitudinal bottom bars 1 and through the ends of the connecting bars 14 extend pivot rods 16 affording a hinged mounting for the ends of 95 the coop. In order to hold the ends of the coop in the closed positions shown in Fig. 1, latches 19 of any desired sort are secured to certain of the top slats 6 and engage the end walls, as clearly shown in Fig. 1. When 100 the ends are in the closed positions shown in Fig. 1, the connecting bars 14 lie between and in contact with the terminal side slats 4 and thus the coop is prevented from collapsing from the form shown in Fig. 1 to 105 the form shown in Fig. 6. In order to collapse the coop, the ends are swung downwardly and inwardly until they lie beneath the bottom, the connecting bars 14 lying against the bottom slats 2 upon 110

the outside of the longitudinal bars 1 as shown best in Fig. 4. In order to hold the end walls folded beneath the bottom, buttons 17 are pivoted to the longitudinal bottom bars 1 intermediate the ends thereof. When, as shown in Fig. 4, the buttons 17 are turned to stand transversely of the bars 1, the buttons engage with the ends of the connecting bars 14 of both end walls 10 at once and thus hold the end walls in place.

The lower ends of the side slats 4 project downwardly below the bottom slats 2, in order that sufficient material may be interposed between the pivot rods 5 and the lower end faces of the slats 4, to prevent breaking. The connecting bars 14 of the end walls are provided in their edges with recesses 18. When the end walls are folded beneath the bottom, as shown in Fig. 4, these recesses 18 receive the projecting lower ends of the side slats 4 when the coop is collapsed as shown in Fig. 6, and permit the collapsing to take place. The connecting bars should lie outside of the longitudinal bars 1 in order that there may be no openings in the coop adjacent the terminal portions of the end walls. This necessitates that the connecting bars 14 be located close to the lower ends of the side slats 4. It is not feasible to diminish the width of the bars 14 in order to permit the lower ends of the side slats 4 to clear the bars, because if such an expedient were resorted to, openings would exist between the outer edges of the bars 14 and the inner edges of the terminal side slats 4, reference being had to

Fig. 1. The utility and the function of the recesses 18, therefore, will be obvious.

Having thus described the invention, what is claimed is:—

1. In a device of the class described, a bottom comprising cross slats and longitudinal bars; ends comprising cross slats and connecting bars, the connecting bars being pivoted to the longitudinal bars of the bottom and being adapted to lie alongside of the longitudinal bars when the ends are folded under the bottom; movable locking means on one longitudinal bar and adapted to engage with certain of the connecting bars of both ends when the ends are folded under the bottom; sides pivoted to the bottom; and a top pivoted to the sides. 45

15 2. In a device of the class described, a top; side slats pivoted to the top; a bottom comprising slats pivoted to the side slats and alternating therewith; ends comprising connecting bars pivoted to the bottom, the ends being adapted to fold beneath the bottom and to rest upon the bottom, the connecting bars of the ends being provided with transverse recesses adapted to receive the extremities of the side slats when the side slats are swung laterally to collapse the top with respect to the bottom. 50

20 In testimony that I claim the foregoing as my own, I have hereto affixed my signature in the presence of two witnesses.

JAMES A. REEDER.
